MELTING AND HOLDING FURNACE

John G. G. Frost, Cleveland, Ohio, assignor to
The National Smelting Company, Cleveland,
Ohio, a corporation of Ohio

Application June 6, 1932, Serial No. 615,503

1. Claim. (Cl. 266—33)

This invention, which is a continuation in part of my copending application Serial No. 538,144, filed May 18, 1931, relates to the art of casting metals, and particularly to improvements in melting and holding furnaces for use in connection with the melting of aluminum and its alloys, and other alloys containing small percentages of aluminum, nickel, tin, or other non-ferrous metals, in which a low iron content is desired. 5 In the casting of metals of this character it is usually the practice to melt the metal in a large furnace and to either cast into ingots and remelt in an iron pot or transfer the molten metal from the large furnace directly to the iron pot for finishing. 10 This practice is usually carried out in all types of casting, whether it be sand casting, permanent mold casting, or die casting.

In each case it is the practice to provide a melting pot that is suitably heated externally by 20 gas, oil or electricity near the casting operation. In the die casting of such metals, the iron melting pot is positioned adjacent the casting machine so that the gooseneck ladle that is generally used can be conveniently operated between the molten 25 metal and the casting machine. This arrangement, and the open pot usually employed in connection with sand and permanent mold casting, makes it practically impossible to use anything other than an externally heated melting and holding pot of iron.

There are many disadvantages that are inherent with the use of the iron pot. In ordinary practice, iron pots are very short lived, even when particular attention is paid to the various 35 linings that are frequently used and, as a result, considerable money is expended in replacing worn out iron pots, and time is wasted in coating such holding pots. Many alloys, and silicon alloys in particular, have a great tendency to 40 dissolve iron from the conventional melting and holding pot of iron, and heretofore it has been very difficult to control the iron content of such alloys because of this disadvantage.

The greatest disadvantage in using the conventional iron melting and holding pot is the tendency 45 of the molten metal to pick up or dissolve iron from the pot and thus increase its iron content. In the casting of non-ferrous metal alloys, it is very essential that the iron content be maintained 50 at a low percentage, since a high percentage iron may have a deleterious effect, such as cracking, on the castings being produced. This is particularly true in die casting, where thin-sectioned, intricate castings are made of aluminum 55 and alloys thereof.

It is one of the objects of the present invention to provide a melting and holding furnace of improved construction which may be conveniently located at the place of casting the metal, and which will overcome the many disadvantages 5 that are inherent with the use of the so-called melting and holding pots of iron.

Another object is to provide a melting and holding furnace for the casting of aluminum, aluminum alloys, and other alloys containing small 10 percentages of aluminum, nickel, tin or other non-ferrous metals which tend to pick up iron when melted, of such construction that considerable time and expense can be saved as compared with the use of conventional holding pots, and 15 which will tend toward a more economic production of satisfactory castings.

Another object is to provide a melting and holding furnace of such construction that the molten metal available for use in the casting 20 operation will be maintained at the proper temperature for casting, and will be free of skimmings or dross.

A further object is to provide a melting and holding furnace for use in connection with the 25 casting of aluminum, aluminum alloys, and other alloys of the character referred to, which may be used adjacent to and in connection with a die casting machine, and in which the molten metal available for use is contained within a chamber 30 of refractory material whereby to avoid an increase in the iron content of the molten metal.

A further object is to provide a melting and holding furnace of preferred form for use in the casting of metals in which the surface of the 35 molten metal available for use is separated from the surface of the molten metal that is being subjected to the melting heat, in order that the body of metal available for use will be free of skimmings and other surface impurities, but subjected to the heat of the metal being melted.

With the above and other objects in view which will be apparent from the following detailed description, the present invention consists 45 in certain features of construction or combinations of parts which will be readily apparent to those skilled in the art to which the invention applies.

In the drawings, which illustrate a suitable embodiment of the invention,

Figure 1 is a side elevation of a melting and holding furnace, portions of the same being broken away and shown in section, and shown in cooperative relation with one type of die casting machine;

50

55

Fig. 2 is a fragmentary view similar to Fig. 1 showing the gooseneck ladle of the die casting machine in its lowered filling position within the molten metal supply chamber;

5 Fig. 3 is a transverse section taken substantially on the line 3—3 of Fig. 1;

Fig. 4 is a vertical section taken substantially on the line 4—4 of Fig. 1, showing the position of the charging opening for the furnace;

10 Fig. 5 is a section taken substantially on the line 5—5 of Fig. 3 showing the position of the flue for the furnace;

Fig. 6 is a fragmentary section similar to Fig. 2 showing a means of allowing a portion of the 15 heat in the heating chamber to be directed against the ladle;

Fig. 7 is a view similar to Fig. 1 of a slightly modified construction, the casting machine being removed;

20 Fig. 8 is a section taken approximately on the line 8—8 of Fig. 7;

Fig. 9 is a fragmentary section showing a modified arrangement of the end portion which spans the furnace walls.

25 Referring specifically to the accompanying drawings, in which like numerals refer to like parts throughout the several views, the melting and holding furnace of the present invention is arranged to replace the conventional iron holding 30 pot that has heretofore been used in the casting of non-ferrous metal alloys. The furnace proper, as shown in the various views, preferably comprises a rectangular shaped shell 1 supported by suitable base members 2. The bottom of the 35 shell is preferably covered with a relatively thick layer 3 of sand or other suitable material, and the layer of sand is surrounded with a liner 4 which may be of common fire brick.

40 A layer of suitable insulation 5 is arranged over the bottom liner 4 and this layer of insulation is in turn completely covered with a relatively thick refractory material 6. The sides and ends of the shell adjacent and above the material are also provided with relatively thick refractory material 7.

45 The melting and holding furnace, as shown in the drawings, is substantially closed over one portion to provide a heating chamber A and is open over the other portion to provide a space 50 B of sufficient size for the ladle of a casting machine to be disposed within the holding furnace and remove molten metal therefrom.

55 The heating chamber A preferably embodies a rectangular shell having side portions 10 extending upwardly from the sides of the main body of the furnace and end portions 11, one of which extends upwardly from one end of the body and the other of which bridges the sides 60 of the main body and extends between the upper side portions 10.

65 The side and end portions 10 and 11 of the enclosure are lined with a suitable refractory 12, and the roof portion 13 which bridges the side and end portions is also preferably of refractory material. In the preferred form of the present invention, the lining 12 of the end portion 11 which spans the furnace walls is preferably provided with a portion 8 depending below the operating level of the molten metal in the furnace but spaced from the bottom 6 to permit the free flow 70 of molten metal from the furnace portion below the heating chamber to the holding portion which is open at B. In cases where drossy metal is 75 being melted or where dross and skimmings re-

sulting from the melting operation is large, it is preferred to employ the downwardly extending portion 8 in order to retain the dross and skimmings within the heating chamber A and prevent it from accumulating on the surface of the metal 5 that is available for use at the open portion B of the furnace. In cases, as will be later pointed out, where relatively clean metal is to be melted, it is not essential to have the lining 12 of the spanning end 11 actually extend below the operating level of the molten metal. In such cases, however, as shown in Fig. 9, the bottom of this end 11 should be sufficiently close to the level of the metal as not to permit too great a loss of heat underneath the same. 15

One end 11 of the enclosure is provided with one or more suitable openings 15 which, in conjunction with suitable burners 16, are arranged to discharge heat into the interior of the enclosure. These burners and openings may also be 20 arranged in the side portions 10 and may be of the gas or oil fired type. Also electrical means may be employed for supplying heat to the heating chamber. As shown in Fig. 4, the lining of the roof B is arched in order to deflect the flame 25 and hot gases downwardly toward the metal in the heating chamber A.

The products of combustion are preferably discharged from the enclosed chamber A through a suitable flue 17 which may be arranged near 30 the level of the metal and in the end containing the heater openings 15, but at a point remote from the openings 15.

One side 10 of the enclosure is formed with a relatively large charging opening 18 which is arranged to be closed by a suitable refractory lined door 19. The furnace is provided with a tap hole opening 20 disposed adjacent the bottom and extending through one of the sides. 40

In the use of the preferred form of the melting and holding furnace of the present invention, the transversely extending wall portion 8 separates the molten metal that is available for immediate use from the metal that is being melted within the chamber A, but does not retard the 45 motion of the molten metal within the furnace, and it is readily apparent that in the preferred form described the metal that is available for use will be free of skimmings or dross. 50

The greatest advantage of the furnace construction described is that the entire melting and holding operation can be carried on right at the casting machine without liability of having the iron content of the molten metal increased through an attack of the molten metal 55 on the holding furnace, which has been the case in the conventional iron holding pots.

Another advantageous feature of the furnace construction is that the motion of the molten 60 metal in the chamber A underneath the wall 8 and into the open portion B, serves to keep the molten metal at the proper temperature for casting.

Another advantageous feature of the furnace construction described is that larger ingots can be melted than is possible in the conventional melting and holding pots, thus reducing the initial cost of the metal and saving considerable 70 time in charging the furnace. Furthermore, ingots having a higher content of iron may be used for charging, since there will be no chance of iron pick-up, which occurs when conventional iron holding pots are used. This thus tends 75

toward the economic production of castings having minimum or low iron content.

A further advantage derived from the use of a melting and holding furnace of the character just described is that suitable and desirable fluxes may be used during the melting and holding of the molten metal. Heretofore this has not been possible when conventional holding pots formed of iron, graphite crucibles or the like were used, since the flux when used in connection with alloys would attack the pot and greatly increase the iron content of the metal being melted when an iron pot is utilized, or would attack the graphite when graphite crucibles are employed.

In order to show the advantageous features of the furnace of the present invention, the same is shown in cooperative relation with one type of die casting machine that is frequently used. In this machine a pair of mold members 21 and 22 are used and the mold member 22 is rigidly secured to a vertically extending member 23, and the mold member 21 is mounted on a reciprocating head 24 that is slidably mounted on a pair of spaced guide rods 25.

The rods 25 at one end are secured to the vertically extending member 23 and at the other end to a support 26. The support 26 carries a rotatable shaft 27 having a crank arm 28 at one end thereof. This crank arm is connected by means of a pitman rod 29 to the reciprocating head 24. This device is arranged adjacent the open holding portion of the furnace, as shown in Fig. 1, and the vertically extending member 23 is provided with a sprue opening 30 which is positioned slightly above the open portion B.

The molten metal is forced under pressure by compressed air into the sprue opening 30 by means of a gooseneck ladle 31 that is arranged directly over the open chamber B. This ladle 31 is formed with an upward extension 32 and is supported by upper and lower pairs of links 33 and 34, respectively. The lower links 34 are pivoted to the ends of crank arms 35 that are rigidly secured to a shaft 36 which is rotatably mounted within a bracket 37 secured to the upwardly extending member 23. The upper links 33 likewise are pivoted to the member 32 and are rigidly secured at their other ends to a shaft 38 that is also mounted in the bracket 37. The shaft 38 is provided with a gear segment 39 which is in mesh with a reciprocable rack 40 and the shaft 36 is provided with a gear segment 41 which is also in mesh with a reciprocable rack 42. When the racks 40 and 42 are reciprocated, the ladle, through the connecting mechanism, is moved into and out of the metal at the open portion of the furnace. In its lowermost position, as shown in Fig. 2, the gooseneck ladle 31 is filled with the molten metal and upon reciprocation of the racks 40 and 42 the ladle 31 is moved upwardly to the position shown in Fig. 1, in which position the open end of the ladle is brought into engagement with the upwardly extending member 32, with its opening in alignment with the sprue opening 30. Pressure is then exerted within the ladle through a compressed air conduit 43 that is in communication with the interior of the ladle, which forces the molten metal within the ladle through the sprue opening 30 and into the chamber 44 formed by the mold members 21 and 22. The pressure within the ladle 31 is maintained until the metal within the mold chamber 44 has set, and then the pressure within the ladle is released and the ladle moved again to its low-

ermost position within the furnace A below the surface of the molten metal, where it is again filled with the molten metal and ready for the casting of the next article that is to be formed in the die casting machine.

In certain types of casting machines it is desirable to heat the gooseneck ladle and this can be accomplished, as shown in Fig. 6, by providing an opening 14 in the spanning end portion 11 to direct heat from within the heating chamber A against the ladle 31. In the case where the depending portion 8 is employed and the wall 11 and its lining 12 terminates slightly above the operating level of the metal, as shown in Fig. 9, sufficient heat may escape underneath the same to provide sufficient heating for the ladle.

In Figs. 7 and 8 I have shown a modified form of furnace, which, although not the preferred form, may be utilized to accomplish the new results of my invention. In this construction, the bottom 50 which is of refractory, slopes gradually upwardly into the heating chamber which makes the furnace relatively shallow underneath the heating chamber but of sufficient area which will provide for more rapid melting on account of the decreased volume of metal without affecting the area exposed to the heat. I have also shown in this construction a charging door 51 in the upper end portion 11. Firing in this case is of the cross or side type, as indicated by the opening 52 which corresponds to the opening 15 in the construction previously described.

In this construction I have eliminated the flue 17 of the construction in Fig. 1, and have provided for the escape of the products of combustion by having the spanning end 11 and its lining 12 terminate slightly above the operating level of the molten metal. In order to deflect the heat away from the casting machine, I have provided a baffle 53, preferably of refractory, spaced slightly in front of the last mentioned end 11, but which is preferably arched a short distance beneath the operating level of the molten metal to permit free flow of metal in the furnace and at the same time prevent the flow of dross, other accumulated impurities and the like, over onto the surface of the metal which is available for use in the holding portion of the furnace. In this construction, however, the edge of the end portion 11 and its lining 12 should not be spaced too great a distance above the operating level of the molten metal, so as not to permit too great a waste of heat from the heating chamber.

The advantages of the furnace of the present invention can be readily appreciated when the melting and holding furnace is used in connection with a die casting machine such as the type shown in the drawings. This arrangement provides a source of clean molten metal that is maintained at the proper temperature for casting.

When the furnace construction is used in connection with permanent mold or sand casting, the molten metal may be removed by a ladle of any conventional construction, and the supply of molten metal will always be clean and be at the right temperature, thus eliminating the disadvantages that are inherent with the conventional iron holding pots that have been used heretofore.

It is obvious from the drawings and foregoing description that the present invention provides means whereby non-ferrous metals such as aluminum and alloys thereof, may be economically cast without danger of increase in the iron content thereof from the holding pot or furnace,

thus tending toward the efficient production of satisfactory castings.

Furthermore, it is to be understood that the particular forms of apparatus shown and described, and the particular procedure set forth, are presented for purposes of explanation and illustration and that various modifications of said apparatus and procedure can be made without departing from my invention as defined in the 10 appended claim.

What I claim is:

A furnace for melting and holding non-ferrous metals in which a low iron content is desired, comprising a refractory lined bottom, end, and 15 side walls, one of said end walls and a portion of each of the side walls extending a substantial distance above the remaining end wall, a cover of refractory material extending over that portion of the furnace defined by the upwardly extending wall portions, and a curtain wall formed of refractory material extending downwardly 20

from the free end of said cover to a point below the normal operating level of the molten metal in the furnace, thereby dividing the furnace into a closed heating portion and an open holding portion, said refractory wall being spaced from the bottom of the furnace to permit molten metal to flow freely from the heating portion into the open portion, means for projecting a flame into the interior of the enclosed heating portion above the level of the metal, a charging opening in said closed portion, a door for closing said opening, and a flue passageway formed in one of the walls of the heating portion to permit the escape of products of combustion, said curtain wall having a relatively small heat directing opening therein 15 relatively near the normal level of molten metal in the furnace and well below said cover for positively directing a portion only of the heat within said heating portion in a predetermined localized path above the metal in said holding portion. 20

JOHN G. G. FROST.
